Willy Schwarz, Spencertown, N. Y.

Application December 4, 1953, Serial No. 27,936

Term of patent 14 years

(Cl. D29—23)

To all whom it may concern:

Be it known that I, Willy Schwarz, a citizen of United States of America, residing at Spencertown, in the county of Columbia and State of New York, have invented a new, original, and ornamental Design for a Wall Plaque or Similar Article, of which the following is a specification, reference being had to the accompanying drawing, forming part thereof.

In the drawing

Fig. 1 is a perspective view of the wall plaque or similar article, showing my new design;

Fig. 2 is a front elevational view thereof;

Fig. 3 is a side elevational view thereof; and

Fig. 4 is a top plan view thereof.

The dominant feature of my design resides in those portions shown in full lines.

I claim:

The ornamental design for a wall plaque or similar article, substantially as shown and described.
